UNITED STATES PATENT OFFICE

GEORGE MALCOLM, OF OLD GREENWICH, CONNECTICUT, ASSIGNOR TO G. R. KINNEY CO., INC., OF NEW YORK, N. Y., A CORPORATION OF NEW YORK

DESIGN FOR A STORE FRONT

Application filed June 17, 1932. Serial No. 44,120. Term of patent 14 years.

To all whom it may concern:

Be it known that I, GEORGE MALCOLM, a citizen of the United States, residing at Old Greenwich, in the county of Fairfield, and State of Connecticut, have invented a new, original, and ornamental Design for Store Front, of which the following is a specification, reference being had to the accompanying drawing, forming a part thereof.

I claim:

The ornamental design for store front as shown.

GEORGE MALCOLM.
